CLAIM

The ornamental design for a windshield wiper, as shown.

DESCRIPTION

FIG. 1 is a perspective view of a windshield wiper showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The showing of a broken tube is to indicate a tube of indeterminate length.
